UNITED STATES PATENT OFFICE

DAVID Y. READ, OF WASHINGTON, DISTRICT OF COLUMBIA, ASSIGNOR TO L C SMITH & CORONA TYPEWRITERS INC., OF SYRACUSE, NEW YORK, A CORPORATION OF NEW YORK

TYPEWRITING MACHINE

Application filed July 6, 1927. Serial No. 203,814.

The present invention relates to typewriting machines and contemplates improvements in the line lock, margin release and paper feeding mechanisms of such machines.

5 In order to provide improvements in a paper feed, permitting writing to the edges of the paper, for the convenience of the operator when gauging the extent and equality of margins to a sheet of writing and for convenience 10 when writing paragraphs with a secondary marginal indentation, and for the general improvement of a typewriter of the front strike type, I have rearranged and redesigned certain of its conventional elements and provided additional elements of novel character, 15 thereby devising a new structure having advantages over prior typewriter structures. The novel features and their functions will be hereinafter fully described and the advantages derived by rearrangement set forth, but it will be appreciated that the invention is not limited in its scope to the exact embodiment disclosed by way of example since, 20 without departure from the teaching thereof, minor alterations and further rearrangements may be suggested by one skilled in the art.

In the drawings:

Figure 1 is a front elevation of a portion of 30 a front strike typewriter, the platen and associated paper feed devices being fully illustrated but portions of the frame and carriage, which are not pertinent to the present invention, being omitted for the sake of clearness;

Figure 2 is a transverse section thru the machine, about on the line 2-2 of Figure 1, portions which have no bearing upon the present invention being omitted;

40 Figure 3 is a perspective view showing in part the novel line lock and paper feed mechanism;

Figure 4 is a plan view of a part of Figure 45 3, partly in section;

Figure 5 is an enlarged view, partially in elevation and partially in section, of the paper deflector plate and its supporting mechanism;

50 Figures 6 and 7 are transverse sections thru one of the combined platen stop and paper holding devices, the two views showing cer-

tain of the operative parts in different positions;

Figure 8 is a section on line 8-8 of Figure 6; and

Figure 9 is a section on line 9-9 of Figure 4. 55

Certain of the corner posts of the frame are indicated at 10 and the platen is indicated at 11, this platen being supported above the top plate 12 of the frame upon a carriage by means of which it may be moved axially in 60 well known manner. It will be observed from an inspection of Figure 2 that the machine is of the front strike type, the printing point being under the eye of the observer as he sits in front of the machine, one of the 65 type bars being indicated at 13 and the margin release key, which is positioned among the other keys, at 14. A universal bar is indicated at 15 and a universal bar locking plate, 70 by means of which the universal bar may be locked against substantial movement and the type thereby prevented from reaching the printing point, being indicated at 16.

Immediately in front of the platen and below the printing line is positioned a toothed 75 margin bar 17, this bar having its ends rigidly secured to the carriage 17a. Immediately underlying this and disposed parallel thereto, is an abutment bar 18 which is mounted on the frame for a limited rocking and longitudinal 80 movement. The abutment bar is likewise toothed, at least at one end, as shown in Figure 3. Adjustably supported upon the margin bar are two stop members, one a line lock stop indicated at 19 and the other a 85 margin stop indicated at 20. Upon the rocking abutment bar are two abutments, a stationary abutment 21, which is rigidly secured to the bar, and an adjustable abutment member 22. In the operation of the machine the 90 line lock stop 19 cooperates with the permanent abutment 21 in limiting the movement of the carriage toward the left and the margin stop 20 cooperates with the adjustable abutment 22 in limiting the movement of 95 the carriage toward the right.

The margin bar 17 is longitudinally grooved upon its top, as shown in Figure 2, and is toothed on its lower edge, the teeth being adapted to interlock with similarly 100

formed teeth of stops 19 and 20 to prevent longitudinal movement of these stops on the bar. The teeth may be, of course, disengaged by the operator in making adjustments. The line lock stop and the margin stop are similarly formed and one only need be specifically described. From Figures 5, 6 and 7 it will be seen that each such stop comprises a member 23, preferably formed of sheet metal, having a portion 23' which extends beneath the bar and lateral arms 24 which extend across the top thereof. From the portion 23' teeth 23² are struck upwardly for the purpose of engaging in the interdental spaces of the rack formed on the margin bar 17.

The arms 24 of the stop may be formed integral with the main portion 23 or formed separately therefrom and brazed or otherwise secured thereon. Thru each of these arms a screw 25 extends (see Figure 5) whereby it is secured to the central portion of a spindle 26. This spindle extends parallel to the margin bar and that portion of the same to which arms 24 are fastened has a flat upper surface and a round lower surface which rests in a correspondingly formed groove in the top of the margin bar. On either side of this central section the spindle is of reduced diameter and has axial threaded apertures formed in its ends, into which screws 27 extend. The peripheries of the circular heads of these screws fit within the groove formed in the margin bar, which groove in fact forms a guiding trackway for the spindle. Slidably mounted upon the spindle is a yoke member 28 the downwardly projecting parallel arms of this yoke being provided with apertures which receive the reduced end portions of the spindle. A coil spring 29 normally presses this yoke to the left (Figure 5) the left hand end thereof striking the head of the left hand screw 27, which forms an abutment or stop therefor. The yoke is free to move toward the right however, under the influence of an impressed force, until its right hand end strikes the head of the right hand screw 27, which likewise constitutes an abutment. In such movement the spring 29 will be compressed and, upon cessation of the force causing such movement, the spring will again expand thereby moving the yoke to the position in which it is shown in Figure 5.

Secured upon the yoke member 28 and preferably formed integral therewith is a deflector plate 30. This deflector plate is curved slightly to substantially conform to the curvature of the platen, against which it normally rests (or against the paper which may overlie the platen). It is slotted at 31 for a reason which will be hereinafter explained, and is also provided with a rectangular cut away portion 32 at the level of the printing line of the machine. The deflector plate may be swung freely about the axis of the spindle altho its movement in one direc-

tion is limited by the platen and in the opposite direction by a locking device hereinafter to be described.

Likewise springing from the stop 23 are two rigid parallel upwardly extending arms 33 which terminate in enlarged portions 33' the outer faces of which are knurled or roughened. A pin 34 passing thru the enlarged upper portions of arms 33 constitutes a pivot upon which a curved roller arm 35 is rotatably mounted. Roller arm 35 terminates in a horizontal portion which carries a rubber roller 36 for pressing the paper against the platen.

Referring particularly to Figures 6 and 7 it will be observed that likewise pivotally supported by the parallel arms 33, which arms, taken together, may be designated a bracket, is a locking arm 37. Arm 37 is curved intermediate its ends, a portion of the arm lying in a plane transverse to the axis of the platen, as seen in Figure 6, and a portion of the arm lying parallel to the axis of the platen as seen in Figures 1 and 3, the last mentioned portion of the locking arm normally lying against the outer face of the associated deflector plate. The inner end of the arm is cut away to provide a cylindrical surface 38 centered about the axis of pivot 34 and a portion of the roller arm 35 is cut away at 39 to likewise provide a cylindrical surface centered on the axis of pivot 34. The surfaces 38 and 39 have substantially the same radius and, when the roller arm 35 is rocked from its full line position (Figure 6) to its dotted line position, cylindrical surface 39 of the roller arm will move into contiguous relationship with surface 38 of the locking arm 37. In this latter position it will be observed that arm 37 is locked against upward rotation about its pivotal axis and hence is caused to act as a brace or strut preventing inward movement of the roller arm supporting bracket, the inner end of the strut resting against the surface of the corresponding deflector plate.

During typing the roller 36 normally lies against the paper and maintains it tight against the platen. It also lies in this position when paper is being fed into the machine. When an erasure is to be made, however, it may be desired to throw back the roller supporting arm into the dotted line position (Figure 6). In this position, as has just been explained, the roller arm supporting bracket is locked against inward movement. This is for the purpose of preventing the operator from accidentally pressing against the top of the bracket and thereby causing outward movement of the lower portion of the stop 23 and disengagement of its teeth 23² from the teeth of the margin bar and hence rendering it impossible for the stop to be accidentally moved lengthwise of the bar, thus changing its adjustment. If it is desired to change the location of the stop the operator simply

presses inwardly upon the enlarged upper end of bracket 33 without retracting the roller supporting arm. As a result of such pressure the bracket locking arm 37 slides upwardly 5 along the surface of the deflector plate to the position in which it is shown in Figure 7 so that the teeth 23² disengage the teeth of the rack whereupon the stop may be quickly adjusted to a new position. A wire spring 40 10 has one end anchored in the central portion 26 of the spindle and its opposite end secured to the lower end of the roller supporting arm. This spring is so designed as to exert a continual upward thrust and hence it is effective 15 to press the roller against the platen when the arm 35 is in its full line position (Figure 6) and to hold this arm away from the platen when it is moved to the dotted line position shown, the line of thrust of the spring being 20 transferred from one side of the pivotal axis of the arm 35 to the other as the arm is moved between its extreme positions. It will further be observed that when the parts are in normal position as shown in full lines in Fig. 25 6 the spring 40 also serves to press into engagement the teeth 23² but that when the bracket 33 is inwardly pressed as in Fig. 7, the urge of the spring becomes neutralized 30 between the pivotal points 26 and 34 thus dispensing with all cramping from spring friction when sliding the stops 19 and 20 along the margin rail.

The rocking abutment bar 18 is provided with spaced longitudinally extending slots 43 thru which project screws 44 by means of which it is loosely secured to the frame. It may obviously have a slight longitudinal movement and the manner in which it is secured to the frame also permits it to have a slight rocking movement about its rear edge or an axis 40 adjacent and parallel thereto. Normally it is held in the position in which it is shown in Figure 3 by an inclined tension spring 45 which has one end attached to its rear edge 45 and the opposite end to a portion of the frame. Pressure upon the margin release key 14, however, results in downward movement of the vertical link 46 and hence in downward rocking movement of the forward edge of the 50 abutment bar. Face 47 of the stationary abutment 21 is an abutment face which cooperates with the line lock stop 19 and this face normally lies in the path of stop 19. Face 48 of the adjustable abutment member 55 22 normally lies in the path of margin stop 20. By actuating the margin release key 14 and downwardly rocking the bar 18 the abutment faces 47 and 48 of the two stops 21 and 22 are moved out of the path of the line lock 60 stop and margin stop respectively, for the purpose of enabling the carriage to be traversed farther in either direction.

The adjustable stop 22 comprises a sheet metal member U-shaped in cross section as 65 shown in Figure 9, and having a handle 50

at one end, the abutment proper, having the abutment face 48, being at the opposite end. It is provided with teeth 51 (Fig. 4) which normally mesh with the teeth of the abutment bar 18 to prevent its longitudinal movement along the bar from left to right. The abutment bar is provided with a groove 52 formed in its upper surface and a rivet 53 which extends thru and is secured in one side of member 22 has its head in the groove, the head of this rivet constituting in reality a pivot about which the entire member 22 may be rocked thru a limited distance and also a retaining member preventing member 22 from being laterally withdrawn from the abutment bar, altho permitting longitudinal movement thereon. A spring 54 has one end secured to member 22 on one side of pivot 53 and its other end presses against the teeth of bar 18. This spring therefore tends to rock member 22 in an anti-clockwise direction (Figure 4) about pivot 53 and hence to maintain teeth 51 in engagement with the abutment bar teeth. From the above description of the adjustable abutment member 22 it is apparent that this member may be drawn to the left by simply exerting the proper pressure upon the finger-piece 50. To move it to the right, however, fingerpiece 50 must first be pushed toward the abutment bar so that teeth 51 become disengaged. The entire member may then be freely moved to the right. By adjusting member 22 longitudinally of the abutment bar its effective abutment face 48 may be placed at various points, thus determining 90 margins of different widths as desired.

It will be observed that the abutment bar 18 has its rear edge notched centrally thereof at 56. One end of a lever 57, pivoted at 58, extends within this notch and the opposite end of this lever engages an arm 60 which extends upwardly from, and is movable with, the rock shaft 61 (Fig. 2) to which the locking plate 16 is secured. By means of this lever connection between the abutment bar 18 and the locking plate 16 the universal bar 15 is locked against movement shortly after the line lock stop 19 strikes the abutment 21 so that the type can no longer be brought into contact with the paper. If, on the other hand, it is desired to type in a few more letters after the line lock stop has become active to prevent further movement of the carriage this may be effected by manipulation of the margin release key which, as has been before explained, depresses the abutment bar 18 and removes the abutment 21 out of the path of the line lock stop 19. The spring 45 having a lateral as well as a downward pull returns the abutment bar 18 along its slot ways 43 immediately upon release of the margin release key, thus raising the locking plate 16. The carriage may have a limited additional movement after this has been done.

The position of adjustable abutment 22 de-

termines, of course, the width of the margin. As it is frequently necessary to write sub-titles or captions in the margin of a type-written instrument or paper it is desirable to have a means whereby this may be accomplished with minimum delay and trouble on the part of the operator. Adjustment of the line stop 20 is to be avoided if possible since the bulk of the instrument is to have a certain definite margin, marginal writing being only necessary at intervals. By the mechanism which I have just described, it is not only possible to set the adjustable stop for the margin of the body of the writing and then write back of it as in the case of marginal notes or captions but it is also possible to employ it as an indenture stop. When used as an indenture stop it is normally kept in its home position at the extreme right of its travel and is moved out a few notches upon occasion for the purpose of indenting a certain paragraph or section of the manuscript. The advantage being the undisturbed positioning of the main stop block 20 during these temporary indentures.

In feeding paper into the machine its forward edge is deflected and guided by the deflector plates so as to pass under the rollers 36. The rollers being spring pressed against the platen, and likewise the deflector plates thru the intermediary of locking arms 37, the paper is firmly supported against the platen at the printing line and for some distance above it so that there is no danger of wrinkling or slippage. The parts are so designed that the pressure rollers are in no danger of being struck by the types as they approach the printing point in either direction but the deflector plates would pass across the printing point and be struck were they not prevented from doing so by contacting, respectively, with the opposite edges of the line finder 63.

As each deflector plate approaches the line finder the edge of this last mentioned member enters the slot 31 of the deflector plate, this entrance being continued until the edge of the line finder strikes the end of the slot. At this point the inner vertical edge of the deflector plate is quite close to the printing point but not in such position as to be struck by the types. Further movement of the carriage, however, results in compression of the spring 29 and relative movement of the deflector plate and carriage so that, while the carriage may be traversed some four or five additional letter spaces, the deflector plate remains stationary and does not pass over the printing point. In this manner a paper finger mechanism is provided which permits writing under the feed roll carried thereby and which automatically feeds under such roll. Paper fingers have previously been designed in which the feed roll or point of pressure overhung the extreme writing point but when these are positioned near the edges of the

paper to permit writing to the extreme edges of the sheet; this being the purpose for which they were designed; they have no control over the sheet of paper when writing across the top edge of the sheet, since the carrying arm for the roller or pressure plate is of necessity off the edges of the sheet in order to be out of the paths of the type when writing on the extreme edges. After having written on the extreme upper corners of a sheet or card the platen is rotated and the paper advances upwardly. There is at this time no control of this sheet by the fingers and consequently it becomes tangent to the roller platen and passes in front of the feed rolls instead of underneath them. In order to correct this it has always been necessary to manually manipulate the paper or card at this juncture in order to place it under the feed rolls. This fault is common to all previous feed rolls situated above the writing point whether supported from below by overhanging paper fingers or from above by a device commonly called a bale. The deflector plate as has been shown serves to feed the paper underneath the roll without interfering with subsequent writing beneath same.

The association of the inner edge of the deflector plates with the points on the paper at which the stops will cause the writing to margin affords the operator a visual indicating means on the writing sheet enabling positioning of these stops without reference to scales. While this thought is not altogether new to the art a certain refinement present in this new structure renders it more easy of accomplishment. It has been found desirable and has come into general use to have in conjunction with the means of stopping the line of writing on either side, means for exceeding these stopping points a few spaces whenever desired, the said stopping means automatically resuming control when returning within their limits. Prior art shows stops with means next the sheet of paper for indicating their position but these stops have to be moved and re-positioned when writing beyond the point indicated. The automatic feature above described obtains in this device when writing beyond the indicated point.

I contemplate minor changes in structure in adapting the invention to various makes of machines and the invention is not limited in the exact design and arrangement of its component elements to the embodiment which has been disclosed by way of example.

What I claim and desire to secure by Letters Patent is:

1. In a typewriting machine, a carriage, a rotatable platen mounted on the carriage and suitable type bars, in combination with an adjustable margin stop mounted on the carriage, and a paper finger mounted on said stop and arranged to slide thereon against the

tension of a spring tending to hold it in normal position.

2. In a typewriting machine, a carriage, a rotatable platen mounted on the carriage and suitable type bars, in combination with an adjustable margin stop mounted on the carriage, and two paper holding devices mounted on said stop and cooperating to hold the paper to the platen, one of said devices being 10 slideable on the stop longitudinally of the carriage.

3. In a typewriting machine, a carriage, a rotatable platen mounted on the carriage, and type bars arranged to strike in front of the platen, in combination with a support mounted on the carriage and two paper guiding devices carried by said support and cooperating to guide a sheet of paper about the platen, one of said devices being operative 15 on the paper above the printing line and the other extending across the printing line, the latter device being mounted upon the support to yield thereon longitudinally of the platen.

25 4. In a typewriting machine, a carriage, a rotatable platen mounted on the carriage, and suitable type bars, in combination with an adjustable margin stop mounted on the carriage, and two paper holding devices 30 mounted on said stop and cooperating to hold the paper to the platen, one of said devices being effective at the printing line and being movable on the stop longitudinally of the carriage and the other device being 35 effective to hold the paper above the printing line.

5. In a typewriting machine, a carriage, a rotatable platen mounted on the carriage, and type bars arranged to strike in front of the platen, in combination with a support 40 mounted on the carriage and two paper guiding devices carried by said support and cooperating to guide a sheet of paper about the platen, one of said devices being fixed 45 against movement longitudinally of the platen relatively to said support and having a roll arranged to bear upon the platen above the printing line and the other device being arranged below the roll and being 50 mounted upon the support to move thereon longitudinally of the platen.

6. In a typewriting machine, a carriage, a rotatable platen mounted on the carriage, and type bars arranged to strike in front 55 of the platen, two pressure rolls supported to bear upon the platen above the printing line, and two paper guides arranged below said rolls, respectively, and extending across the printing line, said guides being supported to yield longitudinally of the platen relatively to said pressure rolls.

7. In a typewriting machine, a carriage, a rotatable platen mounted on the carriage, and suitable type bars, in combination with 60 an adjustable margin stop mounted on the

carriage to limit the normal length of a line of writing, a paper finger mounted on the stop, and means for automatically moving the paper finger relatively to the stop to permit of writing in the margin without disturbing the stop.

8. In a typewriting machine, a carriage, a rotatable platen mounted on the carriage, and suitable type bars, in combination with a device fixed on the frame of the machine, an adjustable margin stop mounted on the carriage, and a paper finger mounted for longitudinal movement on the margin stop and adapted to be automatically moved relatively to the platen by contact with said device to permit of writing in the margin without disturbing said stop.

9. In a typewriting machine, a carriage, a rotatable platen mounted on the carriage, and suitable type bars, in combination with a line finder fixed on the frame of the machine, an adjustable margin stop mounted on the carriage, and a paper finger mounted on the stop, said paper finger having a slot to receive the line finder, for the purpose set forth.

10. In a typewriting machine, a carriage, a rotatable platen mounted on the carriage, and suitable type bars, in combination with an adjustable margin stop mounted on the carriage, a paper finger mounted on said stop and arranged to slide thereon against the tension of a spring tending to hold it in normal position, and a second paper finger mounted on said stop and adapted to cooperate with the platen above the first named finger.

11. In a typewriter, in combination, a frame, a carriage mounted thereon for translatory movement, spaced stops adjustably supported on the carriage, a bar supported on the frame and disposed parallel to the path of travel of the carriage, said bar being laterally movable, spaced abutments on said bar, one of which is adjustable, each abutment normally lying in the path of travel of the corresponding stop, and means for laterally moving said bar to move said abutments out of the path of travel of the stops.

12. The combination set forth in claim 11 in which the bar may be caused to rock about a fixed axis by key operated means.

13. The combination with the platen of a typewriter of a margin bar movable therewith, a margin stop thereon, a paper deflecting plate, a paper roller arm, said plate and arm being pivotally mounted on said stop, and common spring means for normally urging both plate and arm toward the platen.

14. The combination with the platen of a typewriter of a margin bar movable therewith, a margin stop thereon, a paper deflecting plate, a paper roller arm, said plate and arm being pivotally mounted on said stop,

and spring means for normally urging both plate and arm toward the platen.

15. The combination with the platen of a typewriter of a margin bar movable therewith, a stop mounted on the margin bar and adapted to be rocked laterally thereof, being in locking engagement with said bar when in one position and being slidable thereon when in a second position, a paper roller arm pivotally supported on said stop and normally extending toward the platen but adapted to be swung about its pivotal axis away from the platen, and means for maintaining said stop in locking engagement with said bar, 10 when said arm is directed away from the platen.

16. The combination set forth in claim 15 in which the last mentioned means includes a locking arm pivotally supported on the stop, and a deflector plate intermediate said arm and the platen against which the end of the arm normally rests, said locking arm and stop having interlocking portions which are brought into locking engagement when the 25 paper roller arm is swung away from the platen.

17. The combination set forth in claim 15 in which the margin bar is toothed on its lower edge and the stop is provided with 30 teeth for engagement therewith, the arrangement being such that said teeth may be disengaged only when the paper roller arm is extended toward the platen.

18. In a front strike typewriting machine, 35 the combination with a carriage and platen and suitable type bars, of indicating devices close to the platen and adjustable lengthwise of the carriage, said devices being adapted to indicate the ends of a proposed line of writing, one of said devices being yieldable to permit of writing beyond the limit of the proposed line and having means for automatically returning it to its set position when the carriage is retracted.

45 19. In a front strike typewriting machine, the combination with a carriage and platen and suitable type bars, of indicating devices close to the platen and adjustable lengthwise of the carriage, said devices being adapted to indicate the ends of a proposed line of writing, said devices being automatically yieldable on their supports to permit of writing beyond the limits of the proposed line, and means for automatically returning the indicating devices to normal set position.

20. In a typewriting machine, a carriage, a rotatable platen mounted on the carriage, and type bars arranged to strike in front of the platen in combination with two pressure 60 rolls supported to bear upon the platen above the printing line and two paper guides arranged to direct the paper beneath said rolls, respectively, said guides being spring controlled to yield longitudinally of the platen, 65 and to return automatically to set position.

21. In a typewriting machine, a carriage, a rotatable platen mounted on said carriage, type bars arranged to strike in front of the platen, feed rolls positioned above the line of writing, means for automatically guiding paper between said feed rolls and said platen, said means being automatically movable out of the path of said type bars by movement of the carriage in one direction, whereby the entire surface of the paper may be written upon while said paper is being securely held against the platen, and means for automatically restoring said paper guiding means upon reverse movement of said carriage.

75 22. In a typewriting machine, a carriage, a rotatable platen mounted on the carriage and suitable type bars, in combination with a margin stop, a paper guide mounted on said stop adapted to direct the paper around the platen, said guide being mounted to move longitudinally of the platen relatively to the stop.

80 23. In a typewriting machine, a carriage, a rotatable platen mounted on the carriage and suitable type bars, in combination with a paper guide, means for holding the guide adjacent the platen to guide the paper thereon, means whereby the guide may slide longitudinally of the platen, and a spring to return the guide to normal position.

85 24. In a typewriting machine, in combination, a frame, a carriage mounted on the frame for translatory movement, a margin stop adjustably mounted on the carriage, a line lock stop mounted on the carriage, a bar supported on the frame adjacent the carriage and arranged parallel to the path of the carriage, an abutment adjustably supported on said bar for cooperation with the margin stop, a line lock stop abutment mounted on said bar, and means for laterally moving said bar to withdraw the abutment out of the path of travel of the margin stop for the purpose set forth.

90 In testimony whereof I hereunto affix my 110 signature.

DAVID Y. READ.
